ABSTRACT OF THE DISCLOSURE

Process for producing benzene by catalytic hydrodealkylation of toluene. The process is particularly adapted to accept, as a feedstock, relatively low concentration toluene, e.g., aromatics extract from catalytic reformate, comprising 50-80 mol percent toluene and the remainder mainly benzene and xylenes. The additional distillation capacity to separate benzene from the toluene feed may be built into the dealkylator product still. The product still is modified to withdraw the toluene recycle stream from a plate between two reboilers and the toluene feed is introduced to the still below the inlet for dealkylator product.

BACKGROUND OF THE INVENTION

This application relates to a method for the dealkylation of alkyl-substituted aromatic hydrocarbons. More particularly, the invention relates to a method for hydrodealkylating alkyl-substituted aromatic hydrocarbons, such as toluene, in the presence of a catalytic composition of matter.

In recent years, the use of aromatic hydrocarbons, such as benzene, has greatly increased. For example, benzene of a high-grade purity is used as an intermediate in the preparation of styrene monomer which may be polymerized to form a type of rubber. Also, benzene is used as an intermediate in the preparation of phenol, aniline, maleic anhydride, insecticides such as DDT and benzene hexachloride, and as intermediates in the preparation of synthetic fibers, such as some types of nylon.

Another relatively important use of benzene is as an intermediate in the preparation of detergents, such as alkylaromatic sulfonates. These latter compounds are prepared by alkylating benzene with a long chain polymer containing from about 12 to 15 carbon atoms or more in the chain. Following the alkylation of benzene, these long chain alkylbenzenes are then sulfonated by any method well known in the art to produce the corresponding sulfonic acid. The acid may then be neutralized to form the corresponding sulfonate, such as the sodium or potassium salt of the sulfonic alkylaromatic acid.

The dealkylation of alkylaromatic hydrocarbon is, generally, well known in the art and may be performed either thermally or catalytically. The reaction is exothermic in nature and must be carefully controlled in order to prevent a "runaway" reaction, i.e. the reaction temperature increases beyond acceptable and desirable limits. Additionally, the most efficient dealkylation reaction to produce benzene would be to supply as feed relatively high purity toluene so that a minimum of side products, such as gaseous hydrocarbons and polymers, will be formed. However, in commercial practice, high purity toluene can only be obtained economically from the reforming operation or coal tar operation having associated therewith a relatively expensive solvent extraction step which separates the toluene from the other C₈ aromatic hydrocarbons produced, for example, in a typical catalytic reforming step utilizing platinum catalyst.

Accordingly, it would be desirable to have a method for producing benzene via dealkylation of toluene which

can utilize a relatively low concentration toluene feedstock.

SUMMARY OF THE INVENTION

Accordingly, it is an object of the present invention to provide a method for the dealkylation of toluene to produce benzene.

It is another object of this invention to provide a method for producing benzene via hydrodealkylation of toluene in a facile and economical manner.

It is a particular object of this invention to provide an improved method for producing benzene from toluene wherein relatively low concentration toluene feedstocks may be utilized.

In the practice of the present invention there is provided a method for producing benzene via dealkylation of toluene which comprises the steps of: (a) introducing a feed stream comprising toluene into a fractionation zone maintained under fractionation conditions at a locus intermediate the ends of said zone; (b) introducing a herein-after specified benzene-containing stream into said fractionation zone at a locus above said feed locus; (c) supplying heat for fractionation in said fractionation zone through first reboiler means spaced below said feed locus; (d) supplying heat for fractionation in said fractionation zone through second reboiler means spaced below said first reboiler means; (e) withdrawing from said fractionation zone an overhead distillate product stream, a first side-cut benzene stream, a second side-cut toluene stream, and a bottom stream comprising higher-boiling aromatic hydrocarbons; (f) passing at least a portion of said second side-cut stream of step (e) into a dealkylation reaction zone maintained under dealkylation conditions; (g) separating a benzene-containing stream from the effluent of said reaction zone; (h) passing said benzene stream of step (g) into said fractionation zone as specified in step (b); and (i) recovering benzene in high concentration from said fractionation zone.

Another embodiment of this invention includes the method hereinabove wherein said second side-cut fraction of step (e) is withdrawn from a locus between said first and second reboiler means.

In brief, therefore, the present invention provides improvement in the simultaneous processing of the effluent from the reaction zone and a relatively impure feed stream utilizing a single fractionation zone. By operating in the manner specified, a relatively low concentration toluene feed stream may be processed through the system, in such a manner that the actual feed to the dealkylation reaction zone is relatively concentrated thereby providing economy of operation and economy of capital investment in terms of reactor size, pump size, etc. It should also be noted that the single fractionation zone is operated by having at least two (2) reboiler systems, preferably, each located internally to the fractionation column. The benefits to be gained from the present invention reside in this dual reboiler feature and the withdrawal of the relatively concentrated toluene stream from a location within the fractionation zone between the two (2) reboiler means. As will become more evident from the description presented hereinbelow, in the preferred embodiment of the invention, the upper reboiler means utilizes relatively low pressure steam as the external heat media while the lower reboiler means utilizes relatively high pressure steam as the external heating media.

DETAILED DESCRIPTION OF THE INVENTION

The method of this invention utilizes the hydro-dealkylation reaction for removing the alkyl side chains from the benzene nucleus. Therefore, the feedstock to the reaction zone should be a concentrate of toluene; although, to some extent, the xylenes may also be converted to benzene via dealkylation. However, the dealkylation re-

action is not always selective in that xylenes frequently are only reduced to toluene and/or the severity of the reaction is such that the benzene ring is opened or cracked thereby decreasing the aromatic hydrocarbon yield from the overall reaction. However, it is a critical feature of this invention that the feed stream comprise relatively low concentration toluene, e.g. about 50% to 80% toluene on a mol basis with diluting constituents comprising mainly benzene and the xylenes. As those skilled in the art will appreciate from the teachings presented herein, if relatively concentrated toluene is available, there is very little commercial incentive for practicing the method of the present invention. Preferably, the feed stream to the present invention will comprise from 70% to 80% toluene and, generally, will be obtained from a catalytic reforming operation.

Desirably, the dealkylation reaction of the present invention is performed in the presence of a catalyst which may comprise a soluble salt of a metal of Group IV of the Periodic Table, such as, for example, tin chloride, titanium chloride, zirconium oxychloride, tin nitrate, tin sulfate, titanium nitrate, titanium sulfate, zirconium oxybromide, zirconium oxyiodide, etc., is coprecipitated with an alumina sol. A detailed description of the suitable catalyst for the practice of the present invention may be found in U.S. Pat. No. 3,197,523 which issued to Michalko et al. on July 27, 1965. However, it is within the concepts of the present invention that the dealkylation reaction be effectuated thermally, i.e., in the substantial absence of catalytic materials. Those skilled in the art are familiar with the details of dealkylation; therefore, additional description of this well known reaction need not be presented herein.

Suitable dealkylation reaction conditions utilizing the catalytic composite referred to hereinabove will include a temperature from 1,000° F. to 1,500° F. and a pressure from 300 p.s.i.g. to 1,000 p.s.i.g. Desirably, a molar excess of hydrogen is also maintained in the reaction zone in order to reduce the possibility of catalyst deactivation due to deposition of coke or other heavy carbonaceous material upon the catalytically active centers and surfaces of the catalyst. The liquid hourly space velocity through the catalyst bed may range from 0.5 to 5 and the hydrogen to hydrocarbon mol ratio may range from 3:1 to 15:1. Additionally, while the method of this invention may be effected in either a batch type or continuous type operation, it is distinctly preferred that a continuous operation be utilized.

It is to be noted that the fractionation zone of the present invention involves, preferably, a single distillation column having a feed inlet for the dealkylated product stream, a feed inlet for the relatively low concentration toluene stream, a side-cut stream for withdrawing high purity benzene, and a side-cut stream for withdrawing a relatively high purity toluene. These distinctive features are accomplished through the unique technique of having two (2) reboiler means, preferably, located internally within the fractionation zone. It is not intended to limit the present invention to the use of any predetermined numbers of levels of reboilers in as much as one, two, or more reboilers may be utilized within the column. Also, side reboilers or external reboilers may be used in combination with or instead of the internal reboilers where desired within the scope of this invention. In addition, various forms or designs of liquid wells to accommodate the internal reboiler means may be utilized as long as there is proper weir means to effect a liquid overflow from each zone containing a reboiler and a substantially constant liquid level in such zone to permit uniform heating over the reboiler tubes.

Therefore, another embodiment of this invention includes the broad method hereinabove wherein said first and second reboiler means are internal and a portion of said bottoms stream of step (e) is returned to said frac-

tionation zone to provide a liquid seal over said second reboiler means.

Operation of the fractionation zone in accordance with this invention, therefore, removes non-benzene components as an overhead distillate fraction and non-dealkylatable components as a bottoms residue fraction. By way of emphasis, the benefits which are gained from the practice of this invention involve the utilization of the fractionation zone as described above operating in conjunction with a dealkylation reaction zone.

10 Subsequent to the obtaining of a relatively concentration toluene-containing stream from the fractionation zone, this concentrate of toluene is passed into the dealkylation reaction zone operating, preferably, in the presence of a molar excess of hydrogen and a preferred catalytic composite of the type described herein.

The effluent from the reaction zone is then, typically, passed through heat exchange means into a separation zone wherein hydrogen gas for recycle purposes is obtained and returned to the reaction zone. The remaining liquid from the separation zone is then passed into stripping and/or absorption means wherein normally gaseous hydrocarbons are obtained and separated from the benzene-containing dealkylated product stream. This benzene-containing stream is withdrawn from the stripping and/or absorption zone and passed into a treating zone, such as with clay, wherein impurities which might impair the acid-wash color test for benzene are removed. Finally, the clay treated product containing benzene is passed into the fractionation zone at a locus generally intermediate the ends of the fractionation zone and above the inlet locus for the relatively low concentration toluene feed stream which had previously been introduced into such zone.

35 The ultimate benzene product is of relatively high purity in that, typically, it may have a 5.5° C. freeze point. Also, practice of the present invention will typically handle a toluene feed stream containing about 70% toluene and produce a reaction zone feed stream containing at least 90% on a mol basis toluene.

40 The invention may be more fully understood with reference to the appended drawing which is a schematic representation of apparatus for practicing one embodiment of the present invention.

45 DESCRIPTION OF THE DRAWING

It is understood that the drawing as well as the description thereof is presented herein for the sole purpose of illustration and is not intended to limit the method of the present invention beyond the scope of the appended claims. In the interest of simplicity, various heaters, condensers, valves, control instruments, vessel configurations, etc. have been eliminated from the drawing, leaving only those vessels, connecting lines, and block representations which are necessary for a complete understanding of the process.

50 Referring now to the drawing, a relatively low concentration toluene stream diluted with other aromatic hydrocarbons and obtained as a by-product oil from a coke oven operation or from a catalytic reforming operation is introduced into the system via line 10 and passed into fractionation column 11 at a locus intermediate the ends of fractionation column 11. A typical toluene-containing stream may comprise on a commercial scale 154 mols per hour of toluene, 48 mols per hour of benzene, and 12 mols per hour of xylenes. This feed stream enters fractionator 11 at a temperature of about 250° F. and a pressure of about 9 p.s.i.g. Suitable fractionation conditions are maintained in fractionator 11 whereby a light hydrocarbon stream comprising, for example, cyclohexane, is withdrawn as an overhead distillate fraction via line 13 at a temperature of about 195° F. and a pressure of about 5 p.s.i.g.

55 A hereinafter described benzene-containing stream comprising the hydrocarbon effluent from the reaction zone is also introduced into fractionator 11 via line 12

at a locus above said feed locus for line 10. This benzene-containing stream on a commercial scale may comprise 159 mols per hour of benzene, 70 mols per hour of toluene, 1.2 mols per hour of xylene, 2.9 mols per hour of $C_{12}H_{10}$ (diphenyl), 3.2 mols per hour of $C_{10}H_8$ (naphthalene), and 3.8 mols per hour of $C_{14}H_{10}$ (anthracene) and enters fractionator 11 at a temperature of 220° F. and a pressure of about 8 p.s.i.g.

An upper side-cut fraction comprising high purity benzene is withdrawn via line 14 at a temperature of 195° F. and a pressure of about 5 p.s.i.g. Typically, this upper side-cut stream will comprise about 207 mols per hour of 5° C. freeze point benzene.

A lower side-cut stream comprising relatively concentration toluene is withdrawn via line 16 at a temperature of about 275° F. and a pressure of about 12 p.s.i.g. This lower side-cut stream on a commercial basis may comprise 223 mols per hour of toluene, 14 mols per hour of xylene, 2.8 mols per hour of $C_{12}H_{10}$, 3 mols per hour of $C_{10}H_8$, and 3.6 mols per hour of $C_{14}H_{10}$. It should be noted at this point that the material in line 16 comprises about 90% on a mol basis toluene whereas the feed material entering via line 10 comprised only about 72% toluene on a mol basis.

A bottoms stream comprising higher-boiling heavy hydrocarbons (e.g. dicyclic aromatic hydrocarbons) is withdrawn from fractionator 11 via line 15 at a temperature of 405° F. and a pressure of about 12 p.s.i.g. Preferably, the net amount of material in line 15 is withdrawn via line 17 and sent to storage for use as fuel. If necessary or desirable, a portion of the material in line 15 may be passed via line 18 into line 16 for further processing as more fully described hereinbelow.

In accordance with the preferred embodiment of the invention presented hereinabove, fractionator 11 comprises at least two (2) internal reboiler means 23 and 24, respectively. Preferably, reboiler means 23 is heated by relatively low pressure steam (e.g. 150 p.s.i.g.) which passes through reboiler 23 via lines 21. Suitable well means 25 having associated therewith a weir is also utilized in the column in order to maintain a liquid seal over the tubes of reboiler 23.

Similarly, in the preferred embodiment, reboiler 24 is heated by relatively high pressure steam (e.g. 600 p.s.i.g.) which passes through reboiler 24 via lines 22. Well 26 having associated therewith suitable weir means is also a desirable part of fractionator 11 in order to maintain a liquid seal over the tubes of lower reboiler means 24.

As a distinctly preferred manner of operation a cycle of higher-boiling heavy aromatic hydrocarbons is maintained via lines 15 and 20 in continuous fashion in order to maintain a liquid seal over the tubes of lower reboiler means 24.

It is also to be noted that two of the essential features of the preferred embodiment of this invention includes the withdrawal of the toluene concentrate stream via line 16 at a locus between internal reboiler means 23 and 24. By operating in this manner, the higher-boiling heavy aromatic hydrocarbons are rejected from the bottom of the column via line 15 and any toluene constituents therein are stripped out by the added heat which is introduced into the column via internal reboiler 24. Similarly, any benzene which has passed down the column into the vapor-liquid contacting means or trays normally associated with fractionating columns is also stripped out by the heat which is introduced into the column via internal reboiler 23.

Returning now to the toluene concentrate stream now comprising about 90% toluene on a mol basis: this material is now passed via line 19 wherein it is mixed with a hydrogen-containing gas stream from line 27 and passed via line 28 into hydrodealkylation reaction zone 29 which contains, preferably, a dealkylation catalyst. Illustrative of this operation, the total reactor hydrocarbon charge may comprise 224 mols per hour of toluene, 13 mols per

hour of xylene, 2.8 mols per hour of $C_{12}H_{10}$, 3.1 mols per hours of $C_{10}H_8$, and 3.6 mols per hour of $C_{14}H_{10}$. Therefore, with the presence of a molar excess of hydrogen gas from line 27, the combined feed to the reactor in line 28 may comprise 1,776.14 mols per hour of hydrogen, 1,053.53 mols per hour of methane, 80.12 mols per hour of ethane, 19.45 mols per hour of benzene, 226.68 mols per hour of toluene, 13.71 mols per hour of xylene, 2.84 mols per hour of $C_{12}H_{10}$, 3.07 mols per hour of $C_{10}H_8$, and 3.55 mols per hour of $C_{14}H_{10}$ and enters reactor 29 at a temperature of 1,275° F. and a pressure of about 570 p.s.i.g.

The effluent is withdrawn from reactor 29 via line 30 at a temperature of about 1,340° F. and is immediately quenched by a recycle stream from line 33 to a temperature of about 1,000° F. Preferably, the quenching zone is located internal the reactor shell. The quenched effluent is then passed via line 30 into separator 31 which may comprise one or more separation vessels which are maintained under conditions sufficient to separate a hydrogen-containing gas via line 27 which is returned to the reaction zone as previously discussed. As those skilled in the art are familiar, a make-up hydrogen stream from a source, not shown, may also be introduced into line 27. The separator liquid is withdrawn via line 32 and a portion thereof returned via line 33 as quench to reactor 29 in the manner previously discussed. The net amount of separator liquid in line 32 is passed into stripping zone 34 wherein suitable conditions are maintained to produce overhead the normally gaseous materials which are sent via line 35, generally, to a refinery fuel system. The composition of the material in line 35 on a commercial basis may comprise 1.6 mols per hour of hydrogen, 8.2 mols per hours of methane, 2.8 mols per hour of ethane, and .3 mol per hour of benzene. Operating conditions in stripper 34 include an overhead temperature of about 105° F. and an overhead pressure of about 218 p.s.i.g. with a bottoms temperature of about 430° F. and a bottoms pressure of about 220 p.s.i.g.

40 The stripper bottoms material comprising a benzene concentrate is withdrawn via line 36 and passed into conventional clay treating means 37 for the removal therein of certain impurities which might impair the acid-wash color test of the ultimate benzene which is recovered in fractionator 11 previously discussed. The clay treated benzene-containing stream is withdrawn via line 12 and passed into fractionator 11 in the manner previously discussed.

From the description of the invention presented thus far, it can be seen that another embodiment of this invention includes the method for producing benzene via hydrodealkylation of toluene which comprises the steps of: (a) introducing a feed stream comprising relatively low concentration toluene diluted with other aromatic hydrocarbons into a fractionation zone maintained under fractionation conditions at a locus intermediate the ends of said zone; (b) introducing a hereinafter specified benzene-containing stream into said fractionation zone at a locus above said feed locus; (c) withdrawing from said fractionation zone an overhead distillate product stream comprising relatively light hydrocarbons, an upper side-cut stream comprising high purity benzene, a lower side-cut stream comprising relatively concentration toluene, and a bottoms stream comprising higher-boiling heavy hydrocarbons; (d) passing said lower side-cut stream into a hydrodealkylation reaction zone maintained under conditions including the presence of hydrogen gas sufficient to dealkylate toluene to benzene; (e) separating a benzene-containing stream from the effluent of said reaction zone; and (f) passing said benzene-containing stream into said fractionation zone as specified in step (b).

The invention claimed:

1. Method for producing benzene via dealkylation of toluene which comprises the steps of:
 (a) introducing a feed stream comprising from about 50 to 80 mol percent toluene diluted with other aro-

- matic hydrocarbons including benzene into a unitary fractionation zone maintained under fractionation conditions at a locus intermediate the ends of said zone;
- (b) introducing a hereinafter specified benzene-containing stream into said fractionation zone at a locus above said feed locus;
- (c) supplying heat for fractionation in said fractionation zone through first reboiler means spaced below said feed locus;
- (d) supplying heat for fractionation in said fractionation zone through second reboiler means spaced below said first reboiler means;
- (e) withdrawing from said fractionation zone an overhead distillate product stream, a first side-cut benzene stream, a second side-cut toluene stream containing a higher concentration of toluene than said feed stream, and a bottoms stream comprising higher boiling aromatic hydrocarbons;
- (f) passing at least a portion of said second side-cut stream of step (e) into a dealkylation reaction zone maintained under dealkylation conditions;
- (g) separating from the effluent of said reaction zone a stream containing a higher concentration of benzene than said feed stream;
- (h) passing said benzene stream of step (g) into said fractionation zone as specified in step (b); and,
- (i) recovering benzene in high concentration from said fractionation zone as said first side-cut stream.
2. Method according to claim 1 wherein said second side-cut fraction of step (e) is withdrawn from a locus between said first and second reboiler means.
3. Method according to claim 2 wherein said first and second reboiler means are internal and, a portion of said bottoms stream of step (e) is returned to said fractionation zone to provide liquid seal over said second reboiler means.
4. Method according to claim 2 wherein said first and second reboiler means are heated by external heating media.
5. Method for producing benzene via hydrodealkylation of toluene which comprises the steps of:
- (a) introducing a feed stream comprising from about 50 to 80 mol percent toluene diluted with other aromatic hydrocarbons including benzene into a unitary

- fractionation zone maintained under fractionation conditions at a locus intermediate the ends of said zone;
- (b) introducing a hereinafter specified benzene-containing stream into said fractionation zone at a locus above said feed locus;
- (c) withdrawing from said fractionation zone an overhead distillate product stream comprising relatively light hydrocarbons, an upper side-cut stream comprising benzene concentrate, a lower side-cut toluene stream containing a higher concentration of toluene than said feed stream, and a bottoms stream comprising higher-boiling hydrocarbons;
- (d) passing said lower side-cut stream into a hydrodealkylation reaction zone maintained under conditions including the presence of hydrogen gas sufficient to dealkylate toluene to benzene;
- (e) separating from the effluent of said reaction zone a stream containing a higher concentration of benzene than said feed stream; and,
- (f) passing said benzene containing stream into said fractionation zone as specified in step (b).
6. Method according to claim 5 wherein said reaction zone contains a dealkylation catalyst.
7. Method according to claim 1 wherein said feed stream contains about 70 to 80 mol percent toluene.
8. Method according to claim 5 wherein said feed stream contains about 70 to 80 mol percent toluene.
